UNITED STATES PATENT OFFICE.

WILLIAM GORMAN, OF NEW BRITAIN, CONNECTICUT, ASSIGNOR TO THE RUSSELL AND ERWIN MANUFACTURING COMPANY, OF SAME PLACE.

DESIGN FOR KNOB ROSE AND ESCUTCHEON.

Specification forming part of Design No. 7,068, dated December 23, 1873; application filed November 15, 1873.
[Term of Patent 14 years.]

To all whom it may concern:

Be it known that I, WILLIAM GORMAN, of New Britain, in the county of Hartford and State of Connecticut, have invented a new Design for Knob Rose and Escutcheon; and I do hereby declare that the following specification, taken in connection with the drawing, is a full, clear, and exact description thereof.

In the drawing, A is the knob-rose, and B C is the escutcheon-plate. The ornamentation on the concave face of the rose A consists of a series of septfoils, radiating from the band-line which surrounds the socket for the knob-spindle, the spaces between the septfoils being occupied with an ornamental leaf-work design, D. Both the upper and the lower members, B and C, of the escutcheon-plate have their edge bounded by a raised band, a, which defines the peculiar outline or configuration of the plate shown, and the interior space is filled with ornamental scroll and leaf. The outline at the top of the plate is arched, and surmounted by a pointed tip. The arch-line at the base thereof connects with a horizontal line at each side, which, respectively, connect with a continuous outline, following a vertical straight line, an outward curve, an inward straight line, bisected by an inward curve, and continuing downward by a straight line, and an outward curve terminates in a square corner on the upper outer edge of the rose-plate. Below the rose-plate, commencing at its lower outer edge,

each side has an outline composed, consecutively, of an outward point, an outward curve, a straight angular line, a square corner, an inward curve occupied by a scroll, a straight line, a square corner, an outward curve, a straight vertical line, an inward horizontal line, an outward curve, a vertical straight line, and terminal angular lines, joining the corresponding lines on the opposite side, and forming a downwardly-pointed terminal tip.

My design is not limited to the particular scroll and leaf work which constitutes the ornamentation of the escutcheon-plate, for this may be varied or omitted altogether; but it is exhibited in the peculiar configuration or outline of the two members of the escutcheon-plate B C, producing, in combination with the knob-rose, the effect to the eye shown in the drawing.

What I claim is—

1. The design for a knob-rose, composed of septfoils and leaf-work, arranged substantially as described, and shown in the drawing.
2. The configuration or outline of the escutcheon-plate B C, consisting of the straight lines and curves, substantially as described, and shown in the drawing.

WILLIAM GORMAN.
